DESIGN FOR A FOOTED GOBLET OR SIMILAR ARTICLE

Elmer Bell, Mount Pleasant, Pa., assignor to
Bryce Brothers Company, Mount Pleasant, Pa.,
a corporation of Pennsylvania

Application December 9, 1935, Serial No. 59,960

Term of patent 14 years

To all whom it may concern:

Be it known that I, Elmer Bell, a citizen of the United States, residing at Mount Pleasant, in the county of Westmoreland and State of Pennsylvania, U. S. A., have invented a new, original, and ornamental Design for a Footed Goblet or Similar Article, of which the following is a specification, reference being had to the accompanying drawing, forming a part thereof.

In the drawing, the figure is a perspective view of a goblet showing my design.

It is to be understood, however, that while I have illustrated the design of my invention as applied to a goblet, it is equally applicable to a complete line of glass stemware, including, besides goblets, glasses for cocktails, wines, cordials, and various liquids and beverages.

I claim:

The ornamental design for a footed goblet or similar article, substantially as shown and described.

ELMER BELL.
